UNITED STATES PATENT OFFICE.

CARL MIEHLKE, OF HARTFORD, WISCONSIN.

AUTOMATIC DAMPER.

Application filed February 14, 1927. Serial No. 168,004.

This invention relates to automatic dampers, or draft regulators.

Objects of this invention are to provide an automatic damper which will control the draft of a furnace, for instance, and maintain the draft at any fixed or desired amount, irrespective of fluctuations due to atmospheric conditions.

Further objects are to provide a device which is substantially instantaneously responsive, and yet does not produce a violent variation in the draft, but produces a gradual variation so that for a given change, a certain opening of the smoke pipe, chimney or similar part of the equipment, is effected, and for an increase, a further opening is secured, thus giving a graded variation corresponding to the exact fluctuations encountered.

In general, this invention is an improvement over that disclosed in my prior Patent No. 1,600,691 of September 21, 1926, for automatic dampers.

An embodiment of the invention is shown in the accompanying drawings in which:

Figure 1 is a plan view of the device with parts broken away;

Figure 2 is a sectional elevation of the apparatus.

Referring to the drawings, it will be seen that the smoke pipe 1 has been indicated, although it is to be understood that the device may be applied to a chimney directly, if desired. In any case, the smoke pipe or chimney 1 is provided with two lateral outlets, as indicated at 2 and 3, which may be of pipe-like formation. The pipe or outlet 2 extends upwardly at right angles, as indicated at 4, and carries a flap valve 5 pivoted on the side adjacent the flue pipe 1, as indicated at 6. This valve is provided with an angularly bent arm 7 which extends through the flue pipe and through the other lateral outlet or pipe 3. This arm is provided with an upstanding rounded portion 8 for a purpose hereinafter to appear. The weight of the valve 5 is sufficient to overbalance the weight of the arm 8, such arm being made relatively light, so that the valve 5 remains closed under ordinary conditions.

The other outlet or pipe 3 carries a vertical pipe or drum 9 which is relatively larger than the portion 4. This drum is closed at its lower side, and adjacent its upper end is provided with an inwardly projecting annular flange 10 against which a disc or main

valve 11 normally contacts or seats. This main valve 11 is suspended by means of a link 12 pivoted at its upper end to a balancing lever 13. The lever 13 is pivoted in a clip or bracket 14 carried by the drum 9, and is threaded, as indicated at 15, adjacent its outer end. This threaded outer end carries an adjustable weight 16 which may be moved inwardly or outwardly by rotating it, so that the exact adjustment may be secured. Obviously, locking means may be employed for the weight, if desired.

It is to be noted that the detail of supporting the lever 13 to secure the minimum friction is extremely simple. The bracket 14, in reality, is provided with two upwardly extending arms which are bridged by a folded metal member 17 to prevent inadvertent removal of the lever 13. Further, the lever is notched, as indicated at 18, and rests upon the upper edge of the bracket or fulcrum 14 between the upwardly extending arms. Preferably, the bracket 14 is made of relatively hard metal, as well as the lever 13, so that a knife-like bearing edge is secured, and thus the minimum of friction is attained.

In operation, the smoke pipe is connected up in the usual way, and the weight 16 adjusted to the exact requirements, locking means being provided, if desired, for the weight, although it is not thought necessary to illustrate such means in the drawing. This locking means need not be used, for example, if the threads are relatively tight so as to hold the weight against motion. When the draft increases unduly the valve or disc 11 moves downwardly. The motion of the main valve is directly controlled by the suction in the smoke pipe, so that immediately upon an increase in suction the valve opens slightly and relieves this increase in suction. In addition to this, if a further increase should occur, the main valve will contact with the rounded upper portion 8 of the light lever 7 and, consequently, will slightly open the valve 5. Further increase in suction will cause further increase in the opening of the valve 5, so that a graded opening is secured in exact accord with the demand. In this manner, the draft may be kept substantially uniform and thus the maximum efficiency of the furnace attained.

From actual experiments conducted with this type of apparatus, it has been found that the fire remains substantially uniform, irre-

spective of changes in condition of the atmosphere, such as high winds, for example, or other disturbances. This uniform draft secures obvious advantages avoiding the 5 fluctuating draft usually encountered and, consequently, prevents the large waste of fuel due to unusual conditions, and also it has been found, prevents the formation of clinkers to a remarkable degree by maintaining the substantially uniform draft.

It is to be noted further that the device is very light as regards all of its moving parts and, consequently, the inertia of the moving system is very small. The result of this is 15 that the response to variations in suction or draft are substantially instantaneous before any detrimental effect therefrom can occur.

Further, it is to be noted that the device may be made with the utmost cheapness and 20 that it is extremely simple and easy to apply.

In the claims, it is to be understood, that the term "smoke pipe" is intended to cover either the usual pipe or a chimney, or a similar device.

Although the invention has been described in considerable detail, such description is intended as illustrative rather than limiting as the invention may be variously embodied 30 and as the scope of such invention is to be determined as claimed.

I claim:

1. The combination of a smoke pipe provided with two opposed laterally extending 35 pipes opening thereinto, an upstanding drum carried by one of said pipes and provided with an upwardly opening valve controlling admission of air thereto, said valve having a lever extending transversely 40 through the smoke pipe and through the other of said laterally extending pipes, a relatively larger drum carried by said last mentioned laterally extending pipe, an an-

nular flange carried adjacent the upper end of said drum, a disc-like valve adapted to 45 contact with the underside of said flange, and means for supporting said disc-like valve, whereby it may freely float to control the draft and whereby continued downward motion of said disc-like valve will cause 50 such valve to contact with said lever and open said first mentioned valve.

2. The combination of a smoke pipe having two opposed vertical chambers communicating therewith, a downwardly opening valve carried in one of said chambers, lever mechanism urging said valve upwardly, an adjustable weight associated with said lever mechanism, a second valve closing the other of said vertical chambers and having 60 a lever rigid therewith and extending into proximity to said first mentioned valve, and adapted to be struck by said first mentioned valve upon descent of said first mentioned valve whereby when said first mentioned valve moves downwardly below a predetermined point said second valve will open.

3. The combination of a smoke pipe having a vertical chamber communicating therewith and opening through its upper end, a 70 downwardly opening valve closing the upper open end of said vertical chamber, mechanism urging said valve towards closed position, and a second valve opening into said smoke pipe and normally remaining closed, 75 said second valve having mechanism arranged in the path of movement of said downwardly opening valve and actuated by the downward motion of said first mentioned valve to open said second valve.

In testimony that I claim the foregoing I have hereunto set my hand at Hartford, in the county of Washington and State of Wisconsin.

CARL MIEHLKE.
